UNITED STATES PATENT OFFICE.

JOSEPH A. P. BELAIR, OF MONTREAL, QUEBEC, CANADA, ASSIGNOR, BY DIRECT AND MESNE ASSIGNMENTS, OF ONE-FOURTH TO J. J. MACDONALD AND ONE-FOURTH TO RUSSELL M. SCOTT, BOTH OF MONTREAL, CANADA.

OIL BURNER.

Application filed February 14, 1921. Serial No. 444,807.

To all whom it may concern:

Be it known that I, JOSEPH A. P. BELAIR, a subject of the King of Great Britain, and resident of the city of Montreal, in the 5 Province of Quebec and Dominion of Canada, have invented certain new and useful Improvements in Oil Burners, of which the following is a full, clear, and exact description.

10 This invention relates to improvements in oil burners and more particularly to burners of the type used in domestic heating and cooking apparatus.

15 The object of the invention is to provide a burner of simple and inexpensive construction adapted particularly for use in domestic heating and cooking apparatus originally designed to burn coal.

20 A further object is to provide an oil burner which will be safe and reliable in operation and which will require a minimum of attention.

25 A still further object is to provide a burner which will conserve fuel by returning unburned oil.

In the drawings which illustrate the invention;—

30 Fig. 1 is a vertical sectional view illustrating the application of the burner to a domestic heating furnace.

Fig. 2 is a plan view of the burner.

Fig. 3 is a section on the line 3—3, Figure 2.

35 Fig. 4 is a perspective view of one form of combustion plate forming a part of the burner.

Fig. 5 is a section similar to Figure 3 illustrating modifications.

40 Referring more particularly to the drawings, 11 designates the fire-box of a domestic heating furnace having a support 12 for grate bars. According to this invention, a centrally apertured metal plate 13 is mounted on the supports 12 and is covered by an 45 insulating mat 14 of asbestos or other suitable material upon which the burner is mounted by direct contact or by means of legs 15. The burner comprises an annular plate 16 having a plurality of openings 17 therethrough surrounded by flanges 18. The central opening of the annulus is closed by a cup 19 connected to the plate by any suit-

able means such as a bayonet joint 20. A drain pipe 21 leads from the lowest point of the cup 19 to a funnel 22 suspended from the plate by a resilient arm 23. The pipe 21 is so curved as to form a trap between the cup 19 and funnel 22. A pipe 24 leads from the funnel to a point outside the furnace. A spider 25 is mounted on the plate 16, the legs 26 of the spider being hollow and communicating at their lower ends with the openings 17 in the plate and at their upper ends with a centrally disposed opening 27 in the lower surface of the spider. This spider is retained in proper position by the engagement of its legs within the flanges 18. Between the legs of the spider there are provided upwardly sloping flanges or baffles 28. In the top of the spider, there may be provided a centrally disposed opening 29 having a removable cover 30, the opening being spanned by a support 31. The fuel supply pipe 32 may extend up through one of the apertures 17 of the plate and through the spider leg aligned therewith, and be directed toward the centre of the spider where it is connected to a T 33. This T is supported centrally of the spider by a bushing 34 passing through the support 31 and into the T, the bushing being closed by a plug 35. The remaining arm of the T carries a short length of pipe 33a which projects a short distance into the opening 27 and is disposed centrally thereof. The opening 27 is continued through a short depending neck 36 having outwardly projecting spaced lugs 37. A combustion pan 38 is provided below the neck and is supported therefrom by arms 39 which hook over the lugs 37. This pan is disposed above the level of the plate 16 and about midway between the lower end of the neck 36 and the bottom of the cup 19. As will be noted, the pan is quite shallow and is composed of thin material, preferably sheet iron. Fuel flow through the pipe 32 is controlled by a valve 39 located externally of the furnace and held normally in open position by a spring 40 surrounding the valve stem 41. One end of a lever 41 is pivotally connected in any suitable manner to the valve body and bears at an intermediate point of its length upon the valve stem 42. Toward the free end of the

90

lever 41, a pail 43 is supported in position to receive any discharge through the pipe 24.

In Fig. 5 there are shown several slight modifications, any or all of which are of equal importance with and may be substituted for corresponding parts as illustrated in the preceding figures, no one form being preferred over others. The fuel pipe 32 instead of coming up through the spider leg is introduced through an opening 32^a near the top. The combustion pan 38 is supported from below on lugs 19^a formed on the cup 19. The pipe 33^a projects entirely through the air outlet 27 and carries a perforated air mixing and deflecting plate 44 which directs the incoming air in a plurality of streams or jets into different parts of the oil gas or vapor arising from the plate 38, thus giving very perfect combustion. The legs 15 may be omitted and the burner set down on the plate 13.

The operation of the device is extremely simple. Oil is admitted slowly through the pipe 32 and drops into the pan 38, where it is ignited and burns. Air enters the combustion chamber of the furnace around the plate 16 and also flows up through the spider legs and thence downwardly through the neck 36. It will thus be observed that the movement of air through the opening 27 is opposed to the normal direction of the flame of oil burning in the pan 38. The result is that the flame is flattened out and escapes between the legs of the spider and under the baffles 28. This flame soon warms the spider legs and consequently the air flowing therethrough, so that the temperature soon reaches and is maintained at a point where a very good combustion is obtained. If any excess of oil is supplied, the shallow pan very soon overflows and the surplus oil is caught in the cup 19 and runs away through the pipe 21. Any flame is extinguished as the oil passes through the pipe and, even where this is not the case, the formation of a trap in the pipe would prevent the escape of any flame or hot gases. The surplus oil runs through the pipe 24 and into the pail 43 where it is collected. If for any reason, such as a temporary stoppage of the oil supply, the burner should go out, the device will be automatically prevented from flooding in the following manner:—The oil accumulates in the pail 43 and, when a predetermined amount has collected, the weight of the pail acting through the lever 41 depresses the valve stem 42 and closes off the oil supply. If the burner should be improperly regulated, the gradual accumulation of oil in the pail 43 will gradually close the valve 37 until only the proper amount of oil is feeding to the burner.

When it is desired to clean the apparatus, this may be very readily accomplished by

removing the cover 30 and screwing out the plug 33, thus permitting the introduction of a brush to clean out the parts 33 and 33^a. The cup 19 and plate 38 may be removed by a slight rotary motion which will disconnect them from the members supporting them. The resilient support for the funnel 22 enables the same to be pressed out of the path of the pipe 21 during disconnection of the cup 19. The burner is very clean to operate, especially when lighting the same, owing to the fact that the plate 38 is of thin material which rapidly heats up to a point where the oil will vaporize on contact therewith. This feature eliminates much soot when the burner is being lighted and also overcomes a prolonged operation of the burner or discharge of gas after the support has been cut off.

While the burner has been shown with a three-legged spider and of circular form and has been described in connection with a particular heating apparatus, it will be understood that the invention is not limited in any of these respects, as the shape of the spider and the number of legs thereof may be changed at will and the invention may be applied to cooking or other apparatus. It will also be understood that while the device has been shown with only a single combustion plate 38 in the spider that a single spider may contain two or more combustion plates.

Having thus described my invention, what I claim is:—

1. In an oil burner, an air heating and conducting element comprising spaced conduits extending upwardly from their inlet ends and downwardly to a discharge point over the combustion zone, and deflecting plates arranged between said conduits.

2. A device according to claim 1, in which the deflecting plates are arranged at an inclination.

3. In an oil burner, the combination with an air conduit having a downwardly directed outlet, a combustion plate below said outlet, and a drip cup below the combustion plate, of a fuel supply pipe including a down-turned extremity extending into the air conduit outlet, a support spanning the air conduit, a bushing passing through said support and into the fuel supply pipe, a plug in said bushing giving access to the down-turned extremity of the pipe, and a removable plate in said conduit giving access to said plug and to the outlet of the conduit.

4. In an oil burner, an air conduit, a combustion plate in alignment therewith, and an air deflecting plate interposed between the mouth of the conduit and the combustion plate.

5. A device of the class described comprising an air conduit having a downwardly directed outlet, a fuel supply pipe passing

through said outlet, a combustion plate below the outlet in alignment therewith, and an air deflecting plate interposed between the air conduit and combustion plate.

5 6. A device according to claim 5, in which the air deflecting plate is adjustably mounted and movable relatively to the mouth of the air conduit and the combustion plate.

7. A device according to claim 5, in which 10 the deflecting plate is apertured to divide air emerging from the conduit into a plu-

rality of streams and to direct said streams into different parts of fuel vapor arising from the combustion plate.

8. A device according to claim 5, in which 15 the deflecting plate is saucer-shaped, perforated and adjustably mounted on the fuel supply pipe.

In witness whereof, I have hereunto set my hand.

JOSEPH A. P. BELAIR.
